UNITED STATES PATENT OFFICE.

FREDERICK D. GOODLAKE, OF MEMPHIS, TENNESSEE.

DESIGN FOR A DEFFLATING-VALVE KEY.

57,329.

Specification for Design.

Patented Mar. 15, 1921.

Application filed December 20, 1919. Serial No. 346,387. Term of patent 3½ years.

To all whom it may concern:

Be it known that I, FREDERICK D. GOODLAKE, a citizen of the United States, residing at Memphis, in the county of Shelby and State of Tennessee, have invented a new, original, and ornamental Design for a Deflating-Valve Key, of which the following is a specification, reference being had to the accompanying drawing, forming a part thereof.

The figure is a perspective view of the deflating valve key, showing my new design.

I claim:

The ornamental design for a deflating valve key, as shown.

FREDERICK D. GOODLAKE.
